UNITED STATES PATENT OFFICE.

DYER T. KENDRICK, OF WORCESTER, MASSACHUSETTS, ASSIGNOR TO LIVERMORE & KNIGHT COMPANY, OF PROVIDENCE, RHODE ISLAND, A CORPORATION OF RHODE ISLAND.

PRINTING PRESS.

Application filed November 4, 1921. Serial No. 512,852.

To all whom it may concern:

Be it known that I, DYER T. KENDRICK, a citizen of the United States, residing at Worcester, in the county of Worcester and

5 State of Massachusetts, have invented certain new and useful Improvements in Printing Presses, of which the following is a specification.

This invention relates to improvements 10 in printing presses of the type more particularly employed for printing upon cards, booklets or other matter by adding to the matter already thereon the name and in some cases the address of each individual 15 recipient whereby the matter added may be of the same type and present the same general appearance as the rest of the printed matter thereon giving the impression of an individual or exclusive communication; and 20 the object of this invention is to provide such a machine with a type-carrying belt adapted to receive a step-by-step movement to bring the type carrying links of the belt successively into position to print upon the 25 work.

A further object of the invention is to provide means whereby that particular set or group of type in the belt, which is in position to print, may be inked after each printing 30 operation.

The invention further consists in the provision of means for arresting the feed of the belt during any desired number of printing 35 operations.

With these and other objects in view, the invention consists of certain novel features of construction, as will be more fully described, and particularly pointed out in the appended claims.

40 In the accompanying drawings.

Figure 1 is a side elevation of my improved printing press showing the frame partly broken away to better illustrate the operating mechanism, and showing the ink 45 roll carrying guide sectioned on line 1—1 of Figure 2.

Fig. 2 is a perspective view showing a portion of the type carrying chain, the links of which comprise receptacles in which the 50 type or printing blocks may be mounted, these receptacles being flexibly connected together.

Figure 3 is a perspective view showing one of the receptacle chain links in which a plurality of rows of type or other printing devices are set. 55

Figure 4 is a top view of the type receptacle link shown in Figure 3, and illustrating the spring therein for yieldingly binding and locking the type in position. 60

Figure 5 is a central sectional end elevation through the receptacle shown in Figure 4.

It is found in practice very desirable in 65 high grade printed matter such as the printing of invitations, some high class cards and booklets and other matter, to be able to print the name of each individual recipient upon the same using type of the same general character as that of the body of the 70 printed matter so as to present the appearance of an individual communication. To accomplish this result has heretofore been a very slow and expensive operation but which by my improved type belt printing 75 press may be done very rapidly; and the following is a detailed description of one means by which the desired results may be accomplished:—

With reference to the drawings, 20 designates the two side frames of my improved printing press in which are mounted three belt-carrying rolls 21, 22 and 23. The roll 21 is mounted on shaft 24 and is provided on 80 its face with teeth 25 to engage the spaces 26 between the links 27 of the chain 28. On this shaft 24 is fixed a ratchet-toothed driving-wheel 29 which is engaged by the pawl 30 pivotally mounted at 31 on the slide 85 bar 32 and is normally pressed into engagement with its ratchet by means of the spring 33. This slide bar is forked at its lower end 34, to straddle shaft 35 and it is provided with a roll 36 which is engaged by a rotating cam 37 on shaft 35 to be raised to 90 act through the pawl 30 to rotate the ratchet wheel 29 and its drive roll 21, the bar being adapted to return by gravity causing the roll to follow the contour of its cam, the 95 drive shaft 35 being driven from a pulley 38 through the pinion 39 and large gear 40.

In some cases it is found to be of advantage to be able to make a plurality of successive impressions from a single block or

set of type before moving the belt, in which case the pawl 30 is swung back against the slide bar causing the snap 41 to engage the pawl and retain it in inoperative position, 5 until sufficient impressions have been obtained from that block of type after which the pawl may be released and the step-by-step advancing movement of the chain continued.

10 In order to position a single block of type, or that set or group of type carried by a single link in the chain so that it alone will act upon the work to make its impressions or print thereon, I have provided an angularly-shaped bed-block 42 the back of which is supported by the front edges of the frames 20 and its front face is provided with a double incline, the apex of which is flattened substantially the width of one of the type 20 receptacle links of the chain whereby when one of these links with its type rests upon this flattened surface the links on either side thereof lay against the inclined surfaces and are themselves removed from position to 25 engage the work when presented during the printing operation.

It is found in practice of advantage to ink the type while in position to print upon work, so that a number of impressions may 30 be taken from a single set of type if desired, without advancing the chain carrying the same. To do this in a simple and effective way I have mounted a set of ink rolls in an ink-roll carrying slide bar 47, the upper 35 roll of the set being mounted on links pivoted in the carrier bar, the same being pressed inwardly by the springs 51 to cause this uppermost roll to follow over or across the top of the type mounted in the block which is seated in its operating or printing position. 40 This carrier bar is mounted in these edge guides 52, and is actuated by the cam 53, see Figure 1, on the shaft 35, through the connections 54, 55 and 56, whereby when 45 the cam is rotated on the shaft 35 it operates through the connections above described to move the slide bar upwardly and cause the rolls to first pass over the ink disk 57 and then up over the type about to perform the 50 printing operation.

In order to rotate this inking disk 57 upon each operation of the press I have provided a pawl 58 pivoted at 59 to the arm 60, which arm is provided with a latch 61 at 55 its inner end, and a block 62 is positioned on the roll-carrying slide bar 47, so that when the bar is raised this block passes the latch 61 without operating the inking disk but as the bar returns this block 62 engages the latch 61 and rocks the lever on its pivot 63 to raise the pawl 58 to engage and rotate the ink disk 47.

The work may be carried by any suitable 60 means but I have herein shown a platen 64 on the inner face of which it may be de-

posited. This platen being mounted at 65 in the side arms 66 which are pivoted at their lower ends at 67, said arms being connected to the crank 68 on the shaft 35 through the adjustable connection 69 whereby the rotation of shaft 35 causes the platen to advance to press its work against the type in the box 70.

In order to tip this platen up to the proper angle automatically, as it is brought 75 forwardly towards the type, I have provided a tipping arm 71 pivoted at its upper end at 72 to a lug 73 on the platen and at its lower end at 74 to the frame whereby the forward swinging movement of the platen 80 causes it to present its work squarely to the type.

My improved chain is especially constructed for my particular purpose, the same comprising a multiplicity of links providing a type receptacle formed in rectangular or trough shape, its height being a little less than that of the usual or ordinary type and its width being sufficient to receive any desired number of lines of type which may be 90 set therein with the usual spacers 76 and all locked by means of springs 77 and held firmly during a printing operation, or in some cases instead of the ordinary type, 95 lines of type may be mounted in these receptacles, electrotypes or cuts of any description may be removably mounted and locked therein to perform the printing operation.

In order to more securely lock or retain 100 the spring 77 and the type mounted in the receptacle I have bent inwardly as at 78 the upper edges of the receptacle in which the type are set so that when the spring is once forced down beyond the inset edges it 105 is effectually prevented from becoming loosened, or drawn out by the jar or action of the press, yet by this construction the type in these receptacles may be readily removed and replaced by a fresh set as often 110 as desired.

These receptacles may be connected together by ordinary chain links 79 or by any other suitable means to form a continuous 115 chain.

I preferably form these chains in duplicate and provide each with means whereby it may be readily taken apart after it has performed its work, and replaced by another chain having a fresh set of type therein so that the operation of the machine may be continued during the setting of any type in the links of the removed chain thereby 120 losing only that time required to change from one chain to another.

My improved printing press is extremely 125 simple in construction and practical in its operation and by its use I am enabled to add to any printed matter, other matter such as addresses or the like of the recip- 130

ients thereof, or it may be employed for any other similar work for which it is adapted.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A printing press type belt comprising a plurality of trough shaped type receptacles linked together in spaced apart relation, each receptacle being adapted to receive a plurality of lines of type and spacers, a spring carried by each receptacle for binding the type therein, and means carried by the receptacle for retaining the spring in operative position.

2. A type receptacle for a type belt, comprising a trough like structure for the reception therein of a plurality of lines of type and spacers, a leaf spring adapted to lie between the wall of the trough like struc-

ture and the type and spacers, and means carried by the trough like structure for retaining the spring in operative position.

3. A printing press type belt comprising a plurality of trough shaped type receptacles linked together in spaced apart relation, each receptacle being adapted to receive a plurality of lines of type and spacers, a spring carried by each receptacle for securing the type therein and means carried by the wall of the receptacle and overlying the top of the spring.

4. A printing press type belt comprising a plurality of trough shaped type receptacles linked together in spaced apart relation, each receptacle being adapted to receive a plurality of lines of type and spacers, a spring carried by each receptacle for securing the type therein and an inwardly extending member carried by the wall of the receptacles for retaining the spring in operative position.

In testimony whereof I affix my signature.

DYER T. KENDRICK.
